UNITED STATES PATENT OFFICE.

JOHN HIST, OF ALLIANCE, OHIO, ASSIGNOR TO THE DUNHAM COMPANY, OF BEREAL, OHIO, A CORPORATION OF OHIO.

LAND ROLLER OR PULVERIZER.

1,082,806.

Specification of Letters Patent.

Patented Dec. 30, 1913.

Application filed December 30, 1912. Serial No. 739,196.

To all whom it may concern:

Be it known that I, JOHN HIST, a resident of Alliance, county of Stark, and State of Ohio, have invented a new and useful improvement in Land Rollers or Pulverizers, of which the following is a full, clear, and exact description, reference being had to the accompanying drawings, forming part of this specification, in which—

10 Figure 1 is an end view of one form of my improved pulverizer; Fig. 2 is a plan view of the pulverizing rollers, together with their journals the supports being sectioned on the line II—II of Fig. 1; Fig. 3 is a 15 sectional view on the line III—III of Fig. 2, through the journal for the shafts of two of the rollers; Fig. 4 is a sectional view on the line IV—IV of Fig. 3; and Fig. 5 is a 20 sectional view on the line V—V of Fig. 2 through the journal frames for the ends of the shafts of the rollers.

This invention relates to land rollers or pulverizers, and is designed to provide a cheap and efficient device of this character, 25 which is provided with a plurality of sets of rolls in transverse alignment with each other, each of which is adapted to oscillate independently of the other rollers, so that all of the rollers will be in contact with the 30 ground throughout their lengths when going over uneven surfaces.

The precise nature of my invention will be best understood by reference to the accompanying drawings, which will now be 35 described, it being premised, however, that various changes may be made in the details of construction and general arrangement of the parts, without departing from the spirit and scope of my invention, as defined in the 40 appended claims.

In the drawings, the numeral 2 designates the longitudinal angle bars on the main or supporting frame, the ends of which are secured to frames or brackets 3. The lower 45 ends of these brackets 3 engage pins 4, which are connected to forked projections 5, which extend upwardly from journal brackets 6. The pulverizer comprises four rollers 7, each of which is provided with a shaft 8, 50 two of the shafts being journaled in one bracket 6, while the other shafts are secured in the other bracket 6, as can be seen by reference to Fig. 2. The shafts 8 engage the journal brackets 6 at a point slightly be-

yond the central portion thereof, the inner 55 ends of the shafts of one set of rollers being journaled in a journal frame 9, while the inner ends of the other set are journaled in a similar frame 9 in engagement with the other frame 9 at the central portion thereof. The engaging portions of these frames 9 are convexed, as indicated at 9^a; the radii of which are struck from about the center of the journal frames 6, so that the journal frames 9 will be in contact with each other 60 when the various rollers are rocked when passing over an uneven surface.

Connected to the angle bars 2 and extending at right angles thereto is a pole or tongue 10.

70 11 is a draft bar bracket connected to the under side of the pole and extending downwardly therefrom in advance of the rollers, and 12 are draft bars which are pivoted at one end to the bracket 11, and at the other 75 end to the journal frames 9.

It will be readily understood by those familiar with the art that when the pulverizer passes over uneven ground, the rollers 7, 7 at one end may assume an angular position with relation to the rollers at the other end, and at the same time each of the rollers at either end can assume different vertical positions with relation to each other. Also that the shafts will have draft 85 connections at two points with the frame and tongue, so that the shafts of the rollers will always be in a position to permit the rollers to rotate thereon, or to permit the shafts to rotate in their journals.

90 The advantages of my invention result from the provision of a plurality of sets of rollers in which the shafts of all the rollers are connected to journal brackets and frames, which are connected to the main 95 frame in such a manner that the rollers at one end of the main frame can assume an angular position with relation to the rollers at the other end of the main frame, and at the same time maintain the axes of the 100 shafts of the rollers at one end of the frame in approximately the same vertical planes as the axes of the shafts of the rollers at the other end of the main frame and further, from the provision of means for permitting 105 the shafts of the rollers at one end of the frame to assume different vertical positions with relation to the other shaft at the same

end of the frame, and at the same time maintain the shafts at both ends of the frame in approximately the same vertical planes.

5 I claim:

1. A pulverizer having a main frame of approximately rectangular form, a downwardly extending bracket rigidly connected to each end of the main frame, a bracket 10 pivotally connected to each of the first mentioned brackets, a plurality of roller shafts mounted in each of said second brackets and extending on both sides thereof, rollers on both ends of each of said shafts, a tongue connected to the main frame, a downwardly extending draft member 15 connected to the tongue, a second bracket connected to the inner ends of each pair of shafts, and a link connected to each of said last mentioned brackets and the downwardly extending draft member on the tongue; substantially as described.
2. A pulverizer having a main frame, a downwardly extending bracket connected to each end of the main frame, a second bracket 25 swiveled to each of the first mentioned brackets, a pair of shafts mounted in each of said second brackets and extending on both sides thereof, rollers on both ends of each of said shafts, a tongue connected to the main frame, a downwardly extending draft member 30 connected to the tongue, a second bracket connected to the inner ends of each pair of shafts, and a link connected to each of said last mentioned brackets and the downwardly extending draft member on the tongue; substantially as described.

In testimony whereof, I have hereunto set my hand.

JOHN HIST.
